[57] **CLAIM**

The ornamental design for a tongue cleaner, as shown.

DESCRIPTION

FIG. 1 is a front perspective view of a tongue cleaner, showing my new design.

FIG. 2 is a front elevational view thereof.

FIG. 3 is a side elevational view thereof.

FIG. 4 is a rear elevational view thereof.

FIG. 5 is a top plan view thereof.

FIG. 6 is a bottom plan view thereof.

FIG. 7 is a sectional view taken along line 7—7 of FIG. 4.

FIG. 8 is a rear perspective view thereof.

The figure is a plan view of a tongue cleaner showing my new design.

FIG. 1

FIG. 2

FIG. 3

FIG. 8
